STRESSED STRUCTURAL ELEMENT
Harry J. Kahn, 188-49A 71st Crescent,
Fresh Meadows, N.Y. 11365
Filed Aug. 19, 1963, Ser. No. 302,913
13 Claims. (Cl. 52-223)

This invention relates to an improved method and apparatus for prestressing structural members, and more particularly, to a method and apparatus for applying prestressing to structural members of highway, building, tower, and the like fields leading to savings, efficiencies, and economies presently unavailable.

To illustrate one application, highways in the United States are experiencing traffic burdens substantially in excess of design load conditions. For example, highway structures, such as bridges, designed to support live loads of 72,000 pounds, are being subjected to live loads as great as 106,000 pounds. Efforts to control this dangerous situation through load limit notices, traffic laws, truck weighing stations and police supervision have failed. As an alternative to police control, strengthening these structures in accordance with conventional engineering practices would be prohibitively expensive.

Further engineering problems are presented by the current aesthetically and economically inspired trend toward applying materials other than steel to structural tasks. These new materials, such as aluminum, fail to exhibit their optimum structural potential when treated according to conventional structural steel design practices. Thus for a specific design load, the necessarily rigid application of traditional beam equations strictly determine the size, shape and weight of the structural member, leaving to the designer only a small margin for ingenuity, improvement, or individual expression.

Continuous beams, in theory stronger and much stiffer than simple beams, are subject to marked changes in bending stress, reaction and shear by small unequal supporting pier subsidences. The stress changes resulting from unequal pier subsidence produce a highly overstressed beam which must be avoided.

The present invention provides a method and apparatus for reinforcing existing structures and overcoming the disadvantages imposed on new structural materials by traditional engineering design concepts and is particularly adapted to all materials deemed structural.

In accordance with the present invention a stressing device having means for storing measured torsional forces is attached to two or more structural members, and the stored torsional forces are transferred from the storage means to the structure, whereby the size, shape and weight of the structural members are substantially reduced as compared to unstressed structural members designed to support an equivalent load. The torsional force is applied to prestress or load the structural members in a direction opposite from the expected direction of designed structural load application. Consequently, as a design load is imposed on the structure, the prestressing force, as well as the inherent unstressed load bearing capacity of the structure, must be reached before the members are fully loaded.

More particularly, the aforementioned means for storing the measured torsional forces, according to the invention may comprise a pair of coaxial torsion members such as tubes, rod, shafts, bars or the like joined on one end by a transverse connecting plate from which an attachment plate is spaced axially and fixed to the one member while a second attachment plate, also axially spaced from the connecting plate, is attached to the other element. A stressing link applies a measured torsional force by relatively twisting the elements about their common longitudinal axis. Couple arm beams, in engagement with the

2

upper and lower flanges of abutting structural members, are each pivoted to respective attachment plates and fulcrumed over one of the torsion members. Releasing the stressing link permits the torsion members to "unwind," transferring the torsional forces, as a couple, through the couple arm beams to the abutting structural members to prestress or "spring" the members. The storing device may also comprise a vertical torsional member or series of concentric vertical members as later described which exhibits greater efficiencies depending upon space limitations and application.

The invention accordingly provides an economical method and apparatus for increasing the load bearing capacity of present structures by prestressing existing structural components, or enabling selective reduction of beam size in new construction for a given design load condition, according to the magnitude of the prestressing force chosen by the designer. The application of this prestressing technique to new and to existing structures is subject to conventional methods of structural analysis and does not require the use of new mathematical design concepts, as will be explained. By reducing the overall size of the structural members for a given design load, the method and apparatus provided by the present invention, substantially reduce manufacturing, transportation and installation costs and thereby increase the economic attractiveness of new structural materials. By "springing" the members in a continuous beam, according to the invention, overstressing conditions created by foundation settling are naturally reduced as are stresses from moving loads.

For a more complete understanding of the present invention, reference may be had to the accompanying drawings in which:

FIGURE 1 is a front elevational view of one embodiment of the stressing device according to the invention as installed in a conventional highway bridge;

FIG. 2 is an enlarged front elevational view in partial section of the stressing device shown in FIGURE 1;

FIG. 3 is a side elevation in full section of the stressing device shown in FIG. 2 as seen along the line 3-3 of FIG. 2;

FIG. 4 is a top plan view in full section of the stressing device shown in FIG. 2, as seen along the line 4-4 of FIG. 2;

FIG. 5 is a front elevation of another apparatus for practicing the invention;

FIG. 6 is a top plan view in partial section as seen along the line 6-6 of FIG. 5;

FIG. 7 is a plan view in partial section, as seen along the line 7-7 of FIG. 5; and

FIG. 8 is a sectional view of a modified form of stressing device including a coiled or helical spring.

Referring to FIG. 1, a typical torsional force storage means or stressing device 10 embodying the invention is interposed between the abutting ends of two conventional structural members or beams 11 and 12. Beam 12 is supported on a pier or foundation 13 by a fixed bearing 15, while the beam 11 rests on a transversely slidable expansion bearing 16, also resting on pier 13.

The stressing device 10, according to one embodiment of the invention, shown in enlarged FIG. 2, has an inner torsion member 17 such as a bar, rod, shaft, or as illustrated, a tubular member telescoped within an outer tubular member 18. The inner and the outer tubular members 17 and 18 are joined at one end by a transverse annular connecting plate 19 best shown in FIG. 3 and welded or similarly secured to the corresponding ends of the tubular members 17 and 18.

As shown in FIGS. 3 and 4, unconnected ends of the inner and outer tubular members 17 and 18 spaced axially from the annular connecting plate 19 are disposed

nearest the abutting ends of the structural members 11 and 12 and are each respectively fixed to an inner attachment means or plate 20 and an outer attachment means or plate 21.

The couple arm beam 23 transfers measured loadings (FIG. 2) from the prestressing device 10 to an upper flange 24 and a lower flange 25 of the structural member 12. A pair of flange fittings 26 and 27 secured by screws 28, or some similar means, to the inwardly opposing faces of the flanges 24 and 25 provide abutting surfaces for the vertical extremities of the couple arm beam 23 through which a couple, established by the torsional force stored within the stressing device 10, can be transferred to "spring" or prestress the structural member 12. The outer attachment plate 21 and couple arm beam 34 similarly "springs" the structural member 11 through upper and lower flanges 29 and 30, flange fittings 31 and 32. Bolts 22 and 33 (FIGS. 2 and 3) are a means of reacting the dead weight of assemblies 10 and 44.

A stressing link 38, comprising two oppositely threaded members 39 and 40 transversely disposed below the inner tubular member 17 and spaced between the inner and outer attachment plates 20 and 21 protrudes through transverse apertures formed in the lower portions of the couple arm beams 23 and 34 respectively. Flanged head portions 41 and 42, interposed between the couple arm beams 23 and 34 and the lower flange fittings 27 and 32, terminate the extreme ends of the threaded members 39 and 40 to lock the couple arm beams 23 and 34 in joint, inwardly pivoting motion. The inner, mutually opposed ends of the members 39 and 40 are threadedly engaged in a turnbuckle 43.

Accordingly, in order to twist the inner tubular member 17 and the outer tubular member 18 relative to each other and store the torsional force within the device, the turnbuckle 43 is tightened to draw the threaded members 39 and 40 and the lower portions of the couple arm beams 23 and 34 together (FIG. 2) to the predetermined prestressing value. It will be observed that since the couple arm beams, pivoted to the inner and outer attachment plates 20 and 21, and in tangential contact with the inner tubular member 17 are fulcrumed against the inner tubular member 17, this arrangement further enhances the spring-like action of the stressing device 10.

The torsional stress characteristics of the storage device 10 are such that, within the safe shearing stress of the tube material, the twist or angular deflection of the tubular members 17 and 18 is generally proportional to the applied load. Consequently, a linear relationship exists between the work input to the turnbuckle 43 on the stressing link 38 and the torsional force established within the tubular members 17 and 18.

A similarly constructed torsional force storage device 44 can be installed (FIGS. 3 and 4) on the opposite side of the webs 45 and 46 to balance the stress imposed on the beam flanges by the stressing device 10.

In practice, the foundation or pier 13, supporting the two abutting beams 11 and 12 is suitably dimensioned at the cap to provide sufficient area needed to mount the wider spaced bearings.

The relationship between the torsional force established within the tubular members 17 and 18 and the linear separation of the lower ends of the couple arm beams 23 and 34 established by the stressing link 38 can be determined by suitable calibration tests.

A specific torsional force is applied to the stressing device 10 by tightening the turnbuckle 43, drawing the opposing inner ends of the threaded members 39 and 40 together a predetermined distance proportional to the force to be stored within the prestressing device 10. Shims 47 are interposed between the flange fittings and the couple arm beams to match the transverse dimensions of the couple arm beams 23 and 34 in a torsionally stressed device to the transverse separation of the abutting surfaces of the flange fittings 26, 27, 31 and 32.

The device 10 is inserted between the abutting ends of the beams 11 and 12 in engagement with the flange fittings and shimmed into proper adjustment while the companion device 44 is similarly applied (FIGS. 3 and 4) to the structural members 11 and 12 on the other side of the webs 45 and 46.

The turnbuckles are loosened, freeing the beams to press against the flange fittings under the torsional force released within the tubular members. The mechanical force couples so released from the stressing device 10 are transferred to the structural members 11 and 12, to "spring" or prestress the beams. The force couples applied to the structural members 11 and 12 prestress the beams against imposed loadings and make it possible to reduce the beam size required to support such loadings relative to an unstressed beam designed to support equivalent loadings or to support greater loads than a similar unstressed beam.

The torsional force storage device 10 may become a part of the final assembly in structures using simple beams. This permanent incorporation of the stressing device 10 in simple beam structures offers the further advantage of availability to react to some degree additional loads imposed on the element thereby reducing both stress and deflection.

The torsional force storage device 10 can also be used to apply a specific prestressing force in continuous beam structures. In some cases of continuous beams, after application of the prestressing force to the individual stringers, the stringers are interconnected to produce a continuous beam, for example as in a highway bridge, by pouring the concrete deck and interconnecting the individual stringers. When the continuous beam is assembled, the torsional force storage device 10 is removed by tightening the prestressing link 38 and withdrawing the device from abutting interposition between the flange fittings.

As hereinbefore mentioned, the formulae governing the physical characteristics of beams prestressed in accordance with the present invention are developed from conventional structural engineering equations. Values may be chosen by the designer, such that the most economical sizes of device and beam members are obtained. Thus the significant dimensions of a torsional force storage device similar to the device described and illustrated, can be determined from the following analysis:

$$f_{st} = \frac{Tr}{I_p}$$

Where:

f_{st} =torsional modulus of rupture in p.s.i.

50 T =torque in inch pounds

r =radius to extreme fiber in inches

I_p =polar moment of inertia in inches

$$\Theta = \frac{TL}{GI_p} \quad L = GI_p/R$$

Where:

Θ =angle of rotation in radians

L =length of torsion device in inches

60 G =modulus of rigidity in p.s.i.

R =rate of device in inch pounds per radian

The length and polar moment of inertia are adjusted for the characteristics of the individual tubes, bars, or shapes. The material and physical properties of the device, if made for example, from steel or aluminum, can be chosen in accordance with design requirements and derived through the methods advanced in "Plastic Torsional Buckling Strength of Cylinders Including the Effects of Imperfections," by L. H. N. Lee and C. S. Ades.

When the device is of the concentric horizontal configuration, due to practical design considerations, according to the embodiment of the invention illustrated in FIGS. 1 to 4, inclusive, the tubular members 17 and 18 have different lengths and different polar moments of inertia.

Rearranging the basic equations for angular rotation, θ , the inner and outer tube lengths 17 and 18 are:

$$L_{17} = GI_{p17}\theta_{17}/T$$

$$L_{18} = GI_{p18}\theta_{18}/T$$

Assuming B to be the additional length of the inner tube 17, the tube lengths may be equated:

$$L_{17} = L_{18} + B$$

$$GI_{p17}\theta_{17}/T = GI_{p18}\theta_{18}/T + B$$

The twists of the two members must equate to the known or total twist of the assembly:

$$\theta_{\text{Total}} = \theta_{17} + \theta_{18}; \theta_{18} = \theta_T - \theta_{17}$$

$$\therefore GI_{p17}\theta_{17}/T = GI_{p18}(\theta_T - \theta_{17})/T + B$$

$$GI_{p17}\theta_{17}/T = GI_{p18}\theta_T/T - GI_{p18}\theta_{17}/T + B$$

$$I_{p17}\theta_{17} = I_{p18}\theta_T - I_{p18}\theta_{17} + BT/G$$

$$\theta_{17} = (I_{p18}\theta_T + BT/G) / (I_{p17} + I_{p18})$$

Revising this equation in terms of the inner member length

$$L_{17} = (GP_{p17}/T)(I_{p18}\theta_T + BT/G)I_{p17} + I_{p18}$$

A singular or multiple vertical device would abide by the same basic torsional equations with slight modification to the twist equations of this page.

The physical characteristics of structural members pre-stressed by a device made and applied in accordance with present invention can be computed by conventional analytical procedures.

The general differential equation of the elastic curve of a beam may be written:

$$EI \frac{d^2y}{dx^2} = M$$

where M is the bending moment equation in terms of the span length (x). Applying, by way of example, this fundamental equation for beam stiffness to a simple beam of negligible weight subjected to pre-twisting two stressing devices 10, each fixed to the ends of the beam, at $x=0$, $y=0$ and $x=1$, $y=0$, respectively, the equation of the bending moment to the left of any point of examination, P , remains constant at the value of the moment ΔM_0 imposed by the stressing device 10 at $x=0$, $y=0$. Both support reactions, R_1 and R_2 , are zero. Thus:

$$M = -\Delta M_0, R_1 = R_2 = 0$$

The differential equation for the specific beam is:

$$EI \frac{d^2y}{dx^2} = -\Delta M_0$$

Integrating this differential equation twice with respect to x yields:

$$EI \frac{dy}{dx} = \Delta M_0 x + C_1$$

$$EIy = -\Delta M_0 x^2/2 + C_1 x + C_2$$

Using the boundary conditions at $x=0$, $y=0$ and the boundary conditions at $x=1$, $y=0$ the deflection equation may be evaluated:

$$\text{at } x=0 \text{ and } y=0 \quad C_2=0$$

$$\text{at } x=1 \text{ and } y=0 \quad 0 = -\Delta M_0 1^2/22 + C_0; C_1 = \Delta M_0 1/2$$

$$\therefore EIy = -\Delta M_0 X^2/2 + M_0 x/2$$

$$EIy = -\Delta M_0 x/2(x-6)$$

The maximum deflection occurs at the centerline of the beam, or $x=6/2$, and is:

$$EIy = -\Delta M_0 6/4(6/2-6)$$

$$y = \Delta M_0 6^2/8EI$$

The general equation for twist is the value of dy/dx , or:

$$\theta EI = EI(dy/dx) = -\Delta M_0 x + \Delta M_0 6/2 = -\Delta M_0(x-6/2)$$

The twist at the stressing device, where $x=0$, is:

$$\theta = \Delta M_0 6/2EI$$

A further embodiment of the invention, shown in FIGS.

5, 6 and 7, can be used to prestress such structural elements as structural members 50 and 51 for use with buildings, bridges, towers, traveling cranes and the like. In terms of craneways, the members may carry steel capped tracks 52 and 53 on upper flanges 54 and 55. Vertical webs 56 and 57 on the members 50 and 51 are provided with abutting recessed slots 58 and 59 accommodating torsional force storage means 60. The torsional force storage means 60 has a torsion member of tubular, bar or rod-like shape 61 made of metal or the like, vertically disposed within the recessed slots 58 and 59. Attachment means 62 and 63, having upper horizontal couple arm beams 64 and 65 (FIG. 6) and lower couple arm beams 66 and 67 (FIG. 7) are secured by welding or some similar means to the vertical extremities of the torsion member 61. The lower couple arm beams 66 and 67 extend transversely across adjacent respective lower flanges 68 and 69 (FIG. 7) to engage abutting lower flange fittings 70 and 71, fastened by bolts 72, or similarly secured to the inner faces of the flanges 68 and 69. The upper couple arm beams 64 and 65 are similarly engaged (FIG. 5) with flange fittings 73 and 74 to the upper flanges 54 and 55. The engagement between the couple arm beams and the flange fittings is such that the upper couple arm beams 64 and 65 place the upper flange fittings 74 and 75 in tension while the lower couple arm beams 66 and 67 place the lower flange fittings 70 and 71 in compression.

In operation the torsional force storage means 60 is twisted about the vertical axis through a pre-selected angle to store a specific amount of work within the torsion member 61. The upper and lower couple arm beams 64, 65 and 66, 67 are placed in abutting relationship with the respective opposing flange fittings 70, 71, 73 and 74 and the torsional forces stored within member 61 are released. The upper and lower couple arm beams 64, 65, 66 and 67 rotate in opposite directions to tension the upper flange fittings and compress the lower flange fittings thereby establishing two force couples in the horizontal plane. Each couple acts to prestress or "spring" one of the respective members 50 and 51.

FIG. 8 discloses a prestressing device similar to the device disclosed in FIGS. 1 to 4 in which the tubular member 17 is replaced by a coiled or helical spring 80 having one end fixed to an attachment plate 81 and the other end connected to another attachment plate 82 fixed to the end of a tubular member 83. The plate 81 and the adjacent end of the member 83 are connected to couple arm beams 84 and 85, respectively. This device operates to prestress the beams in the same way as the device of FIGS. 1 to 4 inasmuch as the spring 80 or the spring and the tubular member 83 act as torsional stress storing members.

As is apparent from the foregoing, the present invention provides a method and apparatus for prestressing structural members to substantially reduce the overall size and weight of the members necessary to support a specific load.

While a representative embodiment of the present invention has been shown and described for purposes of illustration, various changes and modifications can be made therein as pointed out above without departing from the principles of this invention. Therefore, all such changes and modifications are included within the intended scope of the invention as defined by the following claims.

I claim:

1. A device for prestressing structural members, comprising a resilient torsional force storage means for cooperative engagement with at least two of the structural members, a releasable stressing link, at least two portions on the torsional force storage means adapted to be operatively connected to the stressing link for the selective establishment of a resilient torsionally stressing couple, and attachment means operatively connected to the stor-

age means for transferring the couple from the resilient torsional force storage means to the structural members when the stressing link is released.

2. A device according to claim 1 wherein said torsional force storage means includes a coiled spring.

3. A device according to claim 1 wherein said torsional force storage means includes a helical spring.

4. A device according to claim 1 wherein said torsional force storage means includes a generally cylindrical shell having an inner and an outer tubular member resiliently joined together on one end thereof.

5. A device for prestressing structural members, comprising a generally cylindrical shell having an inner and an outer tubular member resiliently joined together on one end thereof by a transverse connecting plate for cooperation with at least two of the structural members, a releasable stressing link operatively connected to the inner tubular member and to the outer tubular member for the selective establishment of a torsionally stressing couple within the cylindrical shell, and attachment means adapted to transfer the couple from the cylindrical shell to the structural members when the stressing link is released.

6. A device according to claim 5, wherein the attachment means includes an outer transverse attachment plate spaced longitudinally from the transverse connecting plate and in fixed cooperation with the outer tubular member, an inner transverse attachment plate spaced longitudinally from the transverse connecting plate and in fixed cooperation with the inner tubular member, a pair of transversely spaced couple arm beams, each of said couple arm beams operatively fastened to one of the transverse attachment plates, and fittings secured to the structural member flanges adapted to cooperatively receive said couple arm beams for transferring the couple from the cylindrical shell to the structural members when the stressing link is released.

7. A device for prestressing structural members, comprising a pair of concentrically arranged tubes having an inner tube, protruding beyond one end of the outer tube, a transverse connecting plate operatively joining the inner and outer concentric tubes at one end, an outer tube attachment plate fixed to the other end of said outer tube and spaced from the transverse connecting plate, an inner tube attachment plate spaced from the outer tube attachment plate and fixed to the protruding end of the inner tube, a pair of transversely spaced couple arm beams cooperatively interposed between said inner tube attachment plate and said outer tube attachment plate, fastening means pivotally attaching one of said couple arm beams to the inner tube attachment plate and the other of said couple arm beams to the outer tube attachment plate in tangential engagement with the inner tube, a stressing link operatively connecting the pair of couple arm beams for selectively establishing a torsional stressing couple within the inner and outer tubes, and fitting means on the structural members adapted to abut the couple arm beams to transfer the couple from said inner

and outer tubes to the structural members when said stressing link is released.

8. A stressing device according to claim 1 including a plurality of torsional force storage means cooperatively engaging the structural members.

9. A method for stressing abutting structural members, comprising angularly twisting a tubular member, locking the angular twist into the tubular member, attaching one end of said tubular member to one of the abutting structural members, attaching the other end of said tubular member to another of the abutting structural members, releasing the angular twist in the tubular member, and transferring said angular twist forces to prestress the abutting structural members.

10. A method according to claim 9, including fastening the prestressed structural members together, and removing said tubular member from the twisted structural members.

11. A device for prestressing abutting structural members, comprising a generally cylindrical member interposed between at least two of the abutting structural members, at least two pairs of couple arm beams fixed to the transverse extremities of said tubular member, at least two pairs of flange fittings cooperatively engaging said respective couple arm beams with the structural members, one of said pairs of couple arm beams compressing said respective pair of flange fittings and another of said pairs of couple arm beams tensioning said respective pair of flange fittings to pivot vertically the abutting structural members.

12. A device for prestressing abutting structural members, comprising a generally vertical cylinder on multiple coaxial cylinders for storing torsional forces therewithin interposed between the abutting structural members, an upper couple arm beam extending transversely across the structural members and operatively fixed to the upper extremity of said vertical cylinder, a lower couple arm beam extending transversely across the structural members and operatively fixed to the lower extremity of said vertical cylinder, a pair of upper flange fittings cooperatively transferring tension forces from said upper couple arm beam to the structural members, and a pair of lower flange fittings cooperatively transferring compression forces from said lower couple arm beam to the structural members to prestress the structural members.

13. A stressing device according to claim 12 including a plurality of torsional force storage means cooperatively engaging the structural members.
